United States Patent Office

Des. 201,074
Patented May 11, 1965

201,074

PANEL ORNAMENT

La Verne E. Clayton, Rockford, Ill., assignor to Amerock
Corporation, Rockford, Ill., a corporation of Illinois

Filed July 24, 1964, Ser. No. 81,003

Term of patent 14 years

(Cl. D13—6)

I claim:

The ornamental design for a panel ornament, substantially as shown and described.
